[57] CLAIM

The ornamental design for a firearm target backstop, as
shown and described.

DESCRIPTION

FIG. 1 is a front perspective view of a firearm target
backstop showing my new design;

FIG. 2 is a rear perspective view thereof;

FIG. 3 is a top plan view thereof; and,

FIG. 4 is a sectional view thereof taken along line 4—4
of FIG. 1.

*Fig. 1**Fig. 2*

*Fig. 3**Fig. 4*
